UNITED STATES PATENT OFFICE

JOHN A. LOCHBAUM, OF SHYVILLE, OHIO

PITMAN HEAD FOR MOWERS, BINDERS, REAPERS, AND THE LIKE

Application filed July 27, 1928. Serial No. 295,747.

This invention relates to new and useful improvements in cutting devices, and particularly to cutting devices for use in connection with mowing-machines, reapers, and the like machines.

One object of the invention is to provide a head for the cutter bar of the sickle, of such a machine, which may be more easily operated than similar devices now in use.

Another object is to provide a device of this character which can be easily adjusted to its proper position, in the cutting apparatus of such a machine as named above, and which can be adjusted to take up or compensate for wear in the parts.

Another object is to provide a device of this character which can be more easily lubricated, and which obviates the usual "running hot", of the sickle bar or knife, and the slide in which such knife and its head are slidably mounted.

Other objects and advantages will be apparent from the following description when taken in connection with the accompanying drawing.

In the drawing:

Figure 1 is a top plan view of a portion of a cutting mechanism of a reaper and binder, showing the invention applied thereto.

Figure 2 is a side elevation of the knife head.

Figure 3 is a vertical sectional view on the line 3—3 of Figure 1.

Figure 4 is a perspective view of the knife head and a portion of the pitman connected therewith.

Referring particularly to the accompanying drawing, 10 represents the slide or guideway of the knife bar of a mowing machine.

The driving wheel or disk is shown at 13, and is provided with the usual wrist-pin 14, on which is engaged the T-shaped coupling 15. The interior of the leg of the member 15 is threaded to receive one end of the pitman rod 16.

Slidable in the guideway 10 is the knife head member 17, to which is attached the cutter bar 18. The inner end of the knife head 17 is formed with an enlargement 20 having the upper and lower flat faces 21 which engage in the upper and lower walls of

the groove of said guideway. Extending laterally from one side of said enlargement 20 is a stub shaft 22, and disposed on said shaft is the cross head of the T-shaped coupling member 23, said member having its leg receiving one of the threaded ends of the before-mentioned pitman rod 16. The upper side of the cross head of the member 23 is formed with an upwardly extending hollow portion 24, the interior of which communicates with the interior of said cross head of said member 23, said portion 24 being adapted to contain lubricant to be supplied to the parts 23 and 22, for the easy and efficient operation thereof. Suitable lubricant supplying means are mounted on the guideway 10 to provide for the efficient lubrication of the guideway and the contacting portions of the knife head.

When it becomes necessary to take up the wear in T-shaped members, and the wrist-pin and stub shaft, the operator simply turns the rod 16.

What is claimed is:

A knife head comprising an elongated member having means at one end for attachment of a cutter bar and an enlargement at the other end provided with upper and lower flat portions for engagement with the guideway of a mower, an integral laterally extending stub shaft on one side of the enlargement, and a hollow T-shaped member having its transverse head rockably supported on the said shaft and having a threaded shank for adjustable reception of an end of a pitman rod, said transverse head having a longitudinal opening in its upper side provided with upwardly extending surrounding walls.

In testimony whereof, I affix my signature. JOHN A. LOCHBAUM.
